UNITED STATES PATENT OFFICE.

THOMAS D. HOLCOMB, OF BROOKLYN, NEW YORK.

LEAF-TURNER.

SPECIFICATION forming part of Letters Patent No. 445,405, dated January 27, 1891.

Application filed September 27, 1890. Serial No. 366,328. (No model.)

To all whom it may concern:

Be it known that I, THOMAS D. HOLCOMB, a citizen of the United States, residing at Brooklyn, in the county of Kings and State 5 of New York, have invented an Improvement in Leaf-Turners, of which the following is a specification.

This invention is intended specially for turning the leaves of music, and the application can be used upon a piano or upon a music-stand.

Leaf-turners have heretofore been made in which there are arms extending from rings surrounding a fixed shaft, and said arms have 15 been unlatched in succession to permit the springs to turn the arms from the right to the left and carry with them the leaf of the music-book, and in some instances leaf-turners have been brought into action by a treadle- 20 connection.

In my present improvements the leaf-turning arms are constructed in such a way as to be received into latches in a stationary tube, within which tube is a plunger moved pro- 25 gressively and acting upon the arms in suc- 70 cection to liberate them and allow their springs to swing such arms and turn the leaves, and the plunger is moved progressively by a ratchet- et-wheel and pawl acted upon by a pedal.

30 In the drawings, Figure 1 is an elevation of the leaf-turning apparatus. Fig. 2 is a sectional plan in larger size at the line $x-x$, and Fig. 3 is a sectional plan in larger size at the line $y-y$; and Fig. 4 is an edge view of the 75 leaf-turning apparatus.

The music is to be held upon any suitable rack or holder. I have represented the rack A as adapted to a piano, and my turning device may be applied either above the music 40 or below the music. Usually it is preferable to apply the same above the music, especially with upright pianos, in which case there is ample room for actuating devices, and the connection to the pedal can pass over the top 45 of the piano.

In cases where the music-turner is above the music it is advantageous to raise and lower the bottom edge of the music according to the height of the sheet, in order that the upper

edge of the sheet may be near to the flange 50 2, and with this object in view I provide a notched rack 3 upon the music-rack, and a sliding holder B, having a latch 4 to sustain the holder at any point to which it may be raised upon the toothed rack 3, and there is 55 a hinged spring-finger C, that can be drawn out for placing the music between such finger and the rack 3, and when pressed back this finger C, coming at the center of the fold of the music, holds the same firmly against the 60 music-rack A and at whatever height the holder B may be raised to. In line with the toothed rack 3 and center of the sheets of music is a shaft D, held at top and bottom by stationary supports 5 to the upwardly-ex- 65 tended portion of the music-rack A, and there are leaf-turners E adapted to swing around the shaft D, and as many of these leaf-turners are to be provided as desired, according to the number of leaves that the apparatus 70 is adapted to.

Each leaf-turner is made as an arm projecting from a ring 6 surrounding the stationary shaft D, and these rings 6 are kept at the proper distances apart, preferably by 75 short tubes or sleeves 7 slipped upon the shaft D; but these sleeves do not clamp the rings, but allow them to turn freely and also allow for the horizontal portion of the leaf-turners receiving a slight movement up and down, 80 and there are helical springs 8 outside the sleeves 7 and acting against the respective rings 6 to prevent the horizontal portions of the rings dropping by their own weight, one of the sleeves 7 and one of the springs 8 being 85 shown in section in Fig. 1, and each leaf-turner is made with a vertical member terminating, preferably, at the end as a forked spring-clip adapted to grasp the edge of the sheet to be turned, and the vertical members 90 of the leaf-turners are at a progressively-increasing distance from the shaft D, so that such leaf-turners do not come into contact with each other, but stand side by side both before and after the leaf has been turned. 95

Adjacent to and parallel with the shaft D is a tube F, into which undercut notches are made, leaving downwardly-projecting tongues

9, and these tongues are in such positions that the leaf-turners can be swung around and passed into the notches of the tube behind the tongues. Hence such tongues form 5 latches that hold the leaf-turners when they have been swung from the left to the right and connected successively with the upper edges of the leaves, and when such leaf-turners are disengaged in succession they swing 10 the leaves from the right to the left in turning such leaves successively.

In order to swing each leaf-turner a suitable spring is provided. I prefer to use small helical springs G, one end of the spring being 15 connected to the ring 6 and the other end to the back board or rack A, and in such position that the spring will be stretched or distended as the leaf-turner is swung from the left to the right, and a contraction of such 20 spring causes the leaf-turner to be swung from the right to the left when disengaged from the latch-tube F. It is usually preferable to groove the edges of the rings 6, so that the helical springs G will lie against the edges 25 of such rings and within their grooved peripheries when the springs are distended.

In order to unlatch the leaf-turners E successively from the tongues of the latch-tube it is only necessary to provide a plunger I 30 within the tube F and to press such plunger lengthwise of the tube, so that each leaf-turner in succession is moved from behind its tongue and thereby liberated, so that its spring will swing the leaf-turner and turn the 35 leaf, and the plunger then is in position to be acted upon a second time to unlatch the next leaf-turner and allow it to swing. Any suitable means may be made use of for moving the plunger I endwise within the tube F. I 40 prefer to cut the rack of teeth into such plunger and to use a gear K, with its teeth in contact with the rack of the plunger, and adjacent to the gear K is a ratchet-wheel L, acted upon by a pawl N, and the teeth of 45 this ratchet-wheel L are to be so cut that for each movement of the pawl N the plunger I will receive an endwise motion sufficient to unlatch one of the leaf-turners.

The pawl N is preferably made to slide longitudinally within the supports 10, and it is moved in one direction by a spring and in the other direction by a cord O, and this cord is to be led to a treadle or pedal P, so that the latch may be actuated by the foot. This pedal may 50 be held in position beneath the instrument by an extensive strut resting at one end on the floor and pressed at the other end against the underside of the piano; but in case of upright pianos the end of a pedal will project at the 55 front edge of the base of the instrument, and the cord O is to be passed over suitable pulleys adapted to the case of the instrument. I have shown an arm Q connected at one end

to the base of the latch or pawl N, and provided with pulleys 13 and 14 for the cord to 60 pass over. With an upright piano this arm Q will be comparatively short and pass across the top of the piano, and with a square piano such arm should be sufficiently long to extend across the piano. In either instance the pulley 14 at the back end forms a guide for the cord that descends to the treadle. By actuating the treadle whenever the leaf is to be turned the pawl N will move the ratchet-wheel L and gear K and give end motion to the 70 plunger I, so as to unlatch one of the leaf-turners, and the spring of the leaf-turner will swing the leaf-turner from the right to the left and carry the leaf with it.

A stop may be provided upon the plunger 80 I to limit the endwise movement of the same. I have illustrated such a stop by the wire R passing to the edge of the plunger and passing through an eye 15, and having a head 16, which coming in contact with the eye 15 prevents the plunger being drawn entirely out of the latch-tube F.

This leaf-turner being simple and compact can be constructed with a large number of turners, as high as twenty-five or thirty, 90 without occupying too much space, and as it is especially designed to be above the music the turner does not approach the key-board or get in the way of the performer.

I claim as my invention—

1. The combination, with the stationary shaft D, the leaf-turners and their springs, of the notched latch-tube F and plunger I, substantially as set forth.

2. The combination, with the shaft D, of 100 the leaf-turners E, each leaf-turner being formed with a ring 6, the helical spring connected with such ring and with the music-rack, sleeves around the shaft D, between the respective rings, and helical springs surrounding the sleeves, substantially as set forth.

3. The combination, with the leaf-turners and their supporting-shaft and springs, of a latch-tube notched and having tongues 110 against which the leaf-turners are held, and a plunger within the latch-tube, and mechanism for giving to such plunger an endwise movement to unlatch the leaf-turners successively, substantially as set forth.

4. The combination, with the stationary shaft, the leaf turners upon such shaft, and the springs for moving such leaf-turners, of latches for holding the leaf-turners, a sliding plunger acting to separate the leaf-turners from the latches, and a ratchet-wheel and pawl for giving to the plunger an end motion, substantially as set forth.

5. The combination, with the leaf-turners and the latches for holding the same, of the 125 plunger, a rack and gear-wheel for giving end

motion to the same, a ratchet-wheel and pawl for moving the gear, a spring to give motion in one direction to the pawl, and a cord and treadle moving the pawl in the other direction, substantially as set forth.

5. The combination, with the music-rack and the leaf-turners above the music, of a toothed rack 3, a sliding music-holder upon the toothed rack, and a spring-finger for hold-

ing the music when placed in position, substantially as set forth.

Signed by me this 18th day of September, 1890.

THOMAS D. HOLCOME.
